UNITED STATES PATENT OFFICE.

WILLIAM I. HAY, OF MONTREAL, QUEBEC, CANADA.

BOAT CONSTRUCTION.

Application filed May 12, 1923. Serial No. 638,523.

To all whom it may concern:

Be it known that I, WILLIAM I. HAY, a subject of the King of Great Britain, and resident of the city of Montreal, in the Province of Quebec and Dominion of Canada, have invented certain new and useful Improvements in Boat Constructions, of which the following is a full, clear, and exact description.

10 This invention relates to new and useful improvements in fore peak bulkhead construction for vessels and particularly canal or lake vessels which have difficult channels to navigate and where head-on collisions 15 with oncoming vessels, channel banks and other obstructions are of frequent occurrence.

The object of this invention is to provide a strengthened fore peak and shoulders without affecting the carrying capacity of the vessel. Another object is to provide a bulkhead which will allow easy access for repairs to the fore peak and shoulders when the vessel is fully loaded.

25 A further object is to provide a protection for the cargo against any leaks which may occur in the fore peak of the vessel through collision or the like.

In my invention I provide a curved bulkhead in the fore peak of the vessel, said bulkhead extending around the shoulders and forming a compartment between the hull and the bulkhead. Access is gained from the deck to repair any damage due to 30 collision or such like occurrence. The bulkhead is spaced from the hull by structural stay girders of considerable depth, the hull forming the compression flange and the bulkhead forming the lower flange when the vessel is subjected to sudden shock, such as 35 coming in contact with another vessel, the canal bank or other obstruction. Also the bow form of this girder adds greater strength to the construction as some of the loading 40 is transferred into the hull as direct compression stresses.

In the drawings:

Figure 1 is a partial sectional elevation of a vessel showing the bulkhead construction.

50 Figure 2 is a plan view with the deck removed.

Referring more particularly to the drawings, 11 designates the ribs or framing angles of the hull, and 12 the longitudinal framing angles or stringers to which the hull plates 55 13 are riveted. The curved angle frames 14

of the forehold extend around the bow of the vessel and are attached to the hull by the girders 15 at the side of the hull. The fore hold plates 16 are riveted to the curved angle frames and reinforced by suitable vertical angles or ribs. The hold plates are spaced from the hull, the greatest distance being at the fore peak 17 and the least at the point 18 where the shoulders 19 meet the main body 60 of the vessel. Bulb angles 20 are provided joining the frames or ribs of the hull together to give added strength to the fore peak. Angle brackets 21 are also provided between the hold and the hull to form a 65 stiffening means between the plates of the hull and the hold. Stiffening members 22 are also provided between the keel girders 23 and the ribs 11. A plate and angle girder or diaphragm 24 may be placed between the 70 bow and the hold and securely riveted or otherwise secured to both to add strength to the construction, said girder 24 being adapted to extend from the above water line or deck to the keel of the vessel. Apertures 75 25 may also be cut in the diaphragm to allow passage from one compartment to another of the forepeak for making repairs to the hull plates or frame. The curving of the bulkhead which forms the fore part of the hold 80 allows the distance between the bow or fore peak and the bulkhead to be made considerably smaller than the usual type in use at the present time, i. e. the transverse bulkhead. 85

90 The operation of the device is as follows: When any excess loading occurs through collision or the like the said loading is taken up by the girder formed by the hull plates, the hold plates and the stiffening members connecting same. The bulkhead being curved transfers the loading into the side plate of the hull and produces a direct loading on the side plates. In a head-on collision the loading is taken up by a girder formed by the 95 hull and the hold plates, said girder being strongest at the point of load application. Comparing the curved bulkhead construction with the transverse bulkhead construction with regard to carrying capacity of the hold, the space lost through reinforcing the shoulders is more than compensated for by the difference in the length of the hold which may be made greater in the curved bulkhead construction than in the transverse 100 105 bulkhead construction. 110

While in Figure 2 I have shown the fore

hold plate as a continuous curve, it will be obvious that the same result may be obtained by forming the fore part of said hold of a series of flat plates riveted together to form in general contour a curve similar, or nearly so, to that shown in Figure 2.

Having thus described my invention, what I claim is:

In a vessel the combination with a hull including the transverse and longitudinal framing angles, of a series of hold plates riveted to the longitudinal framing angles, curved angle frames extending around the bow of the vessel and attached to the hull by girders at the sides of the hull, forehold plates riveted to the curved angle frames and spaced from the hull, vertical angles re-

inforcing said forehold plates, bulb angles joining the framing or angles of the hull together to give added strength to the fore-peak, angle brackets arranged to form a spacing means between the hull plates and the hold, keel girders, stiffening members provided between the keel girders and the transverse framing angles of the hull, a diaphragm placed between the bow and the hold for reinforcing purposes, said dia- phragm being apertured to give passage to the fore-peak compartments at either side thereof.

In witness whereof, I have hereunto set my hand.

WILLIAM I. HAY.
